UNITED STATES PATENT OFFICE.

WILLIAM HENDRICKSON, OF BROOKLYN, NEW YORK.

COMPOSING-STICK.

SPECIFICATION forming part of Letters Patent No. 310,422, dated January 6, 1885.

Application filed April 15, 1884. (No model.)

To all whom it may concern:

Be it known that I, WILLIAM HENDRICKSON, of Brooklyn, in the county of Kings and State of New York, have invented a new and useful Improvement in Composing-Sticks, of which the following is a full, clear, and exact description.

Reference is to be had to the accompanying drawings, forming a part of this specification, in which similar letters of reference indicate corresponding parts in both the figures.

Figure 1 is a plan view of one of my improved composing-sticks. Fig. 2 is a sectional end elevation of the same, taken through the line $\alpha\alpha$, Fig. 1.

The object of this invention is to promote convenience in using composing-sticks.

The invention consists in a composing-stick made with a recessed knee, and provided with lever-clamps having their inner arms overlapped and their outer arms bent to overlap the under side of the bottom of the stick, and made to clasp the said bottom by a hand-screw passing in through a screw-hole in the said knee, as will be hereinafter fully described.

A represents the bottom, B the back flange, and C the end flange, of an ordinary composing-stick.

D is the knee, the lower part of which is recessed to receive the inner arms of the lever-clamps E F, the inner ends of which overlap each other, as shown in Fig. 2. The levers E F are pivoted to the knee D near its ends. The outer arm of the lever E is bent downward, inward, and upward to pass around the edge of the bottom A and rest against the lower side of the said bottom. The outer arm of the lever F is bent upward,

outward, downward, inward, and upward to pass over the flange B and rest against the lower side of the bottom A. The ends of the outer arms of the levers E F are widened to give them a firm hold upon the bottom A and prevent them from marring the said bottom.

G is a thumb-screw, which passes down through a screw-hole in the knee D, so that its forward end will rest upon the upper one of the overlapped ends of the levers E F. With this construction, by tightening the screw G, the levers E F will be made to clamp the lower side of the bottom A, and thus fasten the knee D securely in place, and by loosening the said screw the levers E F will be loosened, so that the said knee can be readily adjusted into any desired position, and when adjusted can be firmly clamped in place.

Having thus described my invention, I claim as new and desire to secure by Letters Patent—

1. The combination, with the recessed knee of a composing-stick, of lever-clamps pivoted to said knee, and a screw for operating said clamps to cause them to engage the body of the stick, substantially as set forth.

2. A composing-stick consisting of the bottom, back flange, and end, A B C, recessed knee D, bent lever-clamps E F, pivoted in a recess in the knee D and embracing the edges of the bottom and back flange with their bent ends, and overlapped at their free ends, and the screw G, passing through the knee to operate the said levers, substantially as set forth.

WILLIAM HENDRICKSON.
